(57) **CLAIM**

The ornamental design for a bottle for fluid products as shown and described.

DESCRIPTION

FIG. 1 is a top perspective view of a first embodiment of a bottle for fluid products;

FIG. 2 is a front elevational view thereof; a rear elevational view not being shown as it is a mirror image;

FIG. 3 is a right side elevational view thereof; a left side elevational view not being shown as it is a mirror image;

FIG. 4 is a top plan view thereof;

FIG. 5 is a bottom plan view thereof;

FIG. 6 is a top perspective view thereof, showing the bottle body with the cap removed;

FIG. 7 is a top perspective view of a second embodiment of a bottle for fluid products;

FIG. 8 is a front elevational view thereof; a rear elevational view not being shown as it is a mirror image;

FIG. 9 is a right side elevational view thereof; a left side elevational view not being shown as it is a mirror image;

FIG. 10 is a top plan view thereof;

FIG. 11 is a bottom plan view thereof;

FIG. 12 is a top perspective view thereof, showing the bottle body with the cap removed;

FIG. 13 is a top perspective view of a third embodiment of a bottle for fluid products;

FIG. 14 is a front elevational view thereof; a rear elevational view not being shown as it is a mirror image;

FIG. 15 is a right side elevational view thereof; a left side elevational view not being shown as it is a mirror image;

FIG. 16 is a top plan view thereof;

FIG. 17 is a bottom plan view thereof; and,

(Continued)

FIG. 18 is a top perspective view thereof, showing the bottle body with the cap removed.

The broken lines shown in the drawings illustrate portions of the article that form no part of the claimed design.
